BENJAMIN K. DORWART AND GEORGE F. ROTE, JR., OF LANCASTER,
PENNSYLVANIA.

Letters Patent No. 71,146, dated November 19, 1867.

IMPROVEMENT IN FENCES.

The Schedule referred to in these Letters Patent and making part of the same.

TO ALL WHOM IT MAY CONCERN:

Be it known that we, BENJAMIN K. DORWART and GEORGE F. ROTE, Jr., of Lancaster, in the county of Lancaster, and in the State of Pennsylvania, have invented certain new and useful improvements in Fences; and do hereby declare that the following is a full, clear, and exact description thereof, reference being had to the accompanying drawings, and to the letters of reference marked thereon. In the annexed drawings, making part of this specification—

A A represent the pannels of a portable fence, which may be constructed in any of the known and usual ways, as there is nothing peculiar in the pannels themselves. The pannels, after being connected together in any known way, are supported by means of the pivoted braces B B. These braces can be pivoted to the pannels themselves, or to blocks which pass through and connect the pannels, or to the posts of the fence, where posts are used. C represents one of the fence posts with the braces pivoted to it at its upper end. The lower ends of the braces may be secured in any suitable way to the earth. These braces may be turned up and out of the way in ploughing or cutting, or cultivating or ditching, close to the fence, and then returned to their places again when the work is finished.

What we claim as new, and desire to secure by Letters Patent, is—

The braces B B pivoted at their upper ends to the blocks which connect the pannels or to the posts, substantially as and for the purpose set forth.

In testimony that we claim the foregoing we have hereunto set our hands this 31st day of October, 1867.

BENJ. K. DORWART,
GEO. F. ROTE, JR.
